Inventor:

I. J. Baxter
per M. M. & Co
Attorneys.

United States Patent Office.

ISAAC J. BAXTER, OF PEEKSKILL, NEW YORK.

Letters Patent No. 92,511, dated July 13, 1869.

COAL-STOVE.

The Schedule referred to in these Letters Patent and making part of the same.

To all whom it may concern:

Be it known that I, ISAAC J. BAXTER, of Peekskill, in the county of Westchester, and State of New York, have invented a new and useful Improvement in Stoves; and I do hereby declare that the following is a full, clear, and exact description thereof, which will enable others skilled in the art to make and use the same, reference being had to the accompanying drawing, forming part of this specification.

This invention relates to a new and useful improvement in stoves, whereby they are rendered convertible, for different uses, and consists in the construction and arrangement of parts, as hereinafter described.

In the accompanying sheet of drawing—

Figure 1 represents a vertical section of the stove, through the line *x-x* of fig. 2.

Figure 2 is a vertical section, through the line *y-y* of fig. 1.

Similar letters of reference indicate corresponding parts.

This stove is designed for burning coal as fuel, but any suitable fuel may be used, as in other stoves. It consists of a hearth, A, and ash-pit B, with a grate, C, fire-box D, (in the form of an inverted truncated cone)

E is the top of the stove, which is square, or nearly square, with rounded corners, with sides which slope down to the top of the fire-box, as seen in fig. 2.

F represents the oven, which is placed on the stove, enclosing the aperture through the top.

A portion, G, of this oven is fast on the top, and the other or upper part, H, is hinged to G, so that it may be raised, and the top of the stove exposed, for other uses than baking.

One important feature of the stove is, the provision made for heating tailors' "irons." For this purpose, I cover the top of the stove (or the aperture) with a series of corrugated plates, marked *J*, lapped together, so as to support each other, as seen in the drawing.

By this method of forming the bearing-plate for heating tailors' irons, the sudden contraction of a heated plate, caused by contact with a cold mass of iron, is prevented, as the corrugations allow of a cir-

culation between the plate and the bottom of the iron, and, the plate being made in separate parts, as represented, expansion and contraction in the metal cause no damage.

These plates form a bottom for the oven, for baking bread or other articles.

At J, fig. 1, it will be seen that there is a pipe, which connects the stationary portion G with the smoke-pipe K.

The pipe J is provided with a damper, for increasing or diminishing the draught from the oven.

L is a grate, for supporting articles in the oven. A similar grate or gridiron may be used over the stove, for broiling.

For broiling, baking griddle-cakes, and for all cooking-purposes when gas, smoke, or disagreeable vapors are generated, the top of the oven may be closed, and such smoke or vapor be conducted to the chimney, through the pipe J. This is a valuable feature in the stove.

When the corrugated plates *J* are removed, various-sized rings, for accommodating different-sized kettles or vessels, are placed in the aperture in the top of the stove.

m is a drop-door, for introducing fuel.

n is a damper, for regulating the draught of the air to the fire-box, and giving access to the ash-pit.

O is a slide-damper, for admitting air to the oven.

The advantages of this arrangement are many, and must be obvious to all.

Having thus described my invention,

What I claim as new, and desire to secure by Letters Patent, is—

1. In combination with a stove, for heating tailors' "irons," the corrugated plates *J*, more or less in number, arranged substantially as described.

2. The construction, arrangement, and combination of the ash-pit B, fire-box D, top E, and oven F, substantially as and for the purpose herein shown and described.

ISAAC J. BAXTER.
